SAFETY WRINGER

David M. Berry, deceased, late of Oakland, Calif.,
by Eva M. Berry, administratrix, Oakland,
Calif.

Application November 20, 1937, Serial No. 175,661

3 Claims. (Cl. 68—263)

The invention relates to a clothes wringer; and the broad object of the invention is to provide a wringer in which it is substantially impossible for a portion of a person's body to become caught.

Another object of the invention is to provide means for releasing a roller of the wringer, which means is actuated by the involuntary reaction of an operator, should the operator's hand by some remote chance be placed in danger of being caught.

Another object is to provide a wringer in which it is impossible to become scalped or have the hair pulled out, because of the hair becoming caught in the wringer.

Further objects of the invention include the provision of a wringer in which things cannot become wrapped around the rolls; which may be operated safely at high speed; which has no stationary surfaces or edges over which the clothes must drag; which will wring clothes without tearing off buttons; and in which a roller may be quickly reset after release.

The invention possesses other objects and features of advantage, some of which, with the foregoing will be set forth in the following description of the invention. It is to be understood that the inventor does not limit himself to this disclosure of species of his invention, as he may adopt variant embodiments thereof within the scope of the claims.

Referring to the drawings:

Figure 1 is a front elevational view of a wringer embodying the improvements of the invention; and

Figure 2 is a vertical sectional view of the same, taken in a plane indicated by the line 2—2 of Figure 1.

Figure 3 is a fragmentary sectional view taken in the same plane as Figure 2, and shows the roller release toggle on somewhat larger scale.

Figure 4 is a similar fragmentary sectional view, illustrating the release toggle in collapsed position; the toggle in this view being shown in side elevation.

Figure 5 is another fragmentary sectional view, taken in a plane indicated by the line 5—5 of Figure 3, and shows a front elevation of the toggle in extended position.

Figures 6 to 8 are fragmentary views showing the pressure roller and release means in front elevation, and illustrating the several different positions of the release mechanism.

The ordinary clothes wringer comprises a pair of rollers between which the clothes are passed.

For safety purposes the upper roller is frequently

made releasable, and a lever is usually arranged on the upper cross bar of the wringer for releasing the roller. Such wringers do not prevent a person from becoming caught, but simply make it possible for an operator to release herself after being caught. Furthermore, the release means requires independent thought and action on the part of the operator to press the release lever at a time when cool thought and action are not dependable. Another serious defect of these wringers is that when both hands become caught, or the hair of the operator becomes caught, the release lever may be very difficult if not impossible to operate at all. The improved wringer of this invention overcomes these and other disadvantages of the ordinary "roller" wringer.

In terms of broad inclusion, the wringer embodying the invention comprises a web for conveying clothes through the wringer, and means for applying pressure to the clothes on the web. The pressure is preferably applied by a roller overlying the web, and a supporting roller is preferably provided under the web. The supporting roller also preferably functions as a drive roller for moving the web. The pressure roller is releasably mounted, and means are provided for releasing this roller. The release means preferably includes actuating or trigger elements overlying the web adjacent each side of the pressure roller for initiating the release action. Means are also provided for resetting the roller.

In greater detail, and referring particularly to Figures 1 and 2 of the drawings, the wringer embodying the invention comprises a pair of end frames 2 connected together at their lower ends by a pair of spreader plates 3, and at their upper ends by a channel bar 4. The end frames are plates of generally triangular shape, being relatively wide at the bottom and tapering in to the width of the cross bar 4 at the top.

An endless web 6 is arranged at the lower portions of the wringer, and is held taut by a pair of freely journaled rollers 7. Web 6 may be of any suitable flexible material such as rubber. The upper reach of the web is supported at its central portions by a roller 8 mounted on a shaft 9 journaled on the end frames. This roller is positioned to elevate the central part of the web somewhat above its ends, so that both halves of the web slope up toward the center. Supporting roller 8 also preferably functions to drive the web; and is of aluminum, or other suitable material, for frictionally engaging the web. Projections or nodules 11 may be formed on the surface of the roller to still further enhance driving.

engagement with the web. As shown in Figure 1, an end 12 of the roller shaft is preferably squared to receive a drive gear.

A pressure roller 13, also of rubber, is mounted 5 on a shaft 14 journaled on the end frames above the central portions of the web and the supporting roller. This pressure roller is movable up and down relative to the web, and is therefore journaled in suitable blocks 16 slidably mounted in 10 the end frames.

Means are provided for resiliently pressing roller 13 downwardly toward the web, and means are also provided for releasing the pressure on this roller. As shown in Figures 1 and 2, an. 15 arched spring bar 17 is arranged above roller 13 with its ends resting on the slideable bearing blocks 16. A plunger 18 is slidably mounted above the spring bar in a rectangular guideway 19 held by brackets 21 supported centrally of the 20 wringer on the cross bar 4. The plunger is provided with a head 22 for bearing against spring bar 17, and this head is threaded into the plunger for adjustment relative to the bar. When the plunger is bearing down against the spring bar 25 the roller 13 is pressed down against the web, as will be readily understood.

The plunger is held down by a releasable mechanism comprising a slideable block 23 connected to the plunger by a pair of toggle arms 24. When 30 the toggle linkage is extended the adjacent ends of the arms abut and the central pivot 26 is off center to balance the linkage. In this condition a downward thrust on block 23 is transmitted to plunger 18. Block 23 is held down by a cam 27 pivoted in brackets 21 and having an arcuate cam slot 28 in which a pin 29 on the block rides. The cam has an extension 31 providing a handle normally lying against cross bar 4 but adapted to be raised to rotate the cam and elevate block 23. 35

40 When the cam handle is down with toggle arms 24 extended, the plunger 18 is in its lower position, as shown in Figures 1, 2, 3 and 5; and in this position the plunger bears down on spring bar 17 to press roller 13 against the web.

45 Means are provided for releasing the pressure on roller 13. For this purpose a pair of trigger plates 32 are disposed adjacent each side of roller 13 above the web 6. These plates are mounted on cross pins 33 slidably mounted in angularly 50 disposed slots 34 in the end frames. The cross pins also have fixed thereon a pair of trigger arms 36 pivotally connected together at 37; one of the arms being curved over to clear the spring bar. A shaft 38 is journaled on the end frames and 55 carries a cam 39 disposed adjacent elbow pivot 26 of the toggle linkage. The shaft also carries a lever 41 connected to the common pivot 37 of trigger arms 36. An opening is provided in the wall of guideway 19 between toggle linkage 24 60 and cam 39, and a spring plate 42 is fastened to the guideway to project down past the flattened side of cam 39.

When either of the trigger plates 32 is moved in any direction, the movement is transmitted 65 to lever 41, causing rotation of cam 39. Rotation of the latter cam, in either direction, presses plate 42 inwardly against elbow pivot 26 to upset the toggle linkage. This unbalancing of the toggle causes the latter to collapse, thus releasing 70 the pressure of plunger 18 on spring bar 17. The pressure of roller 13 against the web is thereby released, and the roller is free to move upwardly.

When it is desired to rebalance or reset the linkage it is only necessary to raise handle 31, 75 thereby elevating block 23 to extend toggle links

24. Upon subsequent lowering of handle 31 with the toggle linkage extended, the plunger is forced down against spring bar 17 to press roller 13 against the web. Figures 6 to 8 illustrate the various steps in releasing and resetting the mechanism. Figure 6 shows the parts in operative position with handle 31 down and toggle links extended to press plunger 18 against spring bar 17. In this position the roller 13 is pressed against web 6 for purpose of wringing clothes 10 passing between the web and pressure roller. 5

Figure 7 shows the relationship after the toggle linkage has been collapsed to release the pressure on the roller. The toggle is shown fully collapsed to illustrate the full distance that the pressure 15 roller is free to move up. Pressure roller 13 is shown separated from web 6, the amount of this separation of course depending upon what is between the roller and web tending to lift the roller up. 20

Figure 8 shows handle 31 rotated around to lift block 23 and extend the toggle linkage. When the handle is then rotated back the plunger 18 is pressed down against spring bar 17 to place the parts in the operative position shown in Figure 6. 25 Thus, in order to reset the mechanism it is only necessary to swing handle 31 around and back again.

In the operation of the wringer it will be observed that the clothes are placed upon web 6 at 30 a point remote from the bite between the pressure roller and web. This keeps the operator's hands away from the danger point. Furthermore, the trigger plates 32 being disposed above the web adjacent each side of the pressure roller absolutely prevent an operator's hand from being caught by the wringer, because if the hand is moved in toward the pressure roller the arm will strike the overlying plate to trip the release mechanism. Also, if the operator's hair be 40 caught, there is no chance of the head being drawn in to pull out the hair or scalp the operator, because the head will first strike a trigger plate to release the roller. 35

Still further, it is impossible for a piece of 45 clothes to wrap around a roller in the wringer, because the lower drive roller 8 is protected by the web, and if an article tends to wrap around the roller 13 it will be peeled off by one of the 50 plates 32. Another feature of the wringer is that there is no fixed element or drain plate over the edge of which the clothes have to be pulled. As a result, the tearing of clothes, or the pulling of buttons therefrom, is largely eliminated. 55

It is claimed:

1. A wringer comprising a web for conveying clothes through the wringer, a releasably mounted roller for applying pressure to the clothes on the web, an extended toggle for holding the roller in operative position, means for collapsing the toggle to release the roller, and a release plate extending longitudinally over the web and operatively connected with said collapsing means. 60

2. A wringer comprising a releasably mounted 65 roller, an extended toggle above the roller for holding it in operative position, means for collapsing the toggle to release the roller, and means engageable with the upper end of the toggle for lifting the collapsed toggle for extending it 70 and for lowering the extended toggle to reset the roller. 75

3. A wringer comprising a releasably mounted roller, a plunger slidably mounted above the roller for holding it in operative position when 75

the plunger is down, an element slidable above the plunger, a toggle connecting said element and plunger and providing a compression link between the latter parts when the toggle is extended, means for collapsing the toggle to allow the plunger to move up to release the roller, and

means for lifting said element to extend the toggle and for lowering the element to move the plunger down to reset the roller.
